UNITED STATES PATENT OFFICE.

CURT KRIEGER, OF LOUISVILLE, KENTUCKY.

HAIR-DRYING COMB.

1,145,492.

Specification of Letters Patent.

Patented July 6, 1915.

Application filed January 6, 1915. Serial No. 823.

To all whom it may concern:

Be it known that I, CURT KRIEGER, a citizen of the United States, residing at Louisville, in the county of Jefferson and State 5 of Kentucky, have invented certain new and useful Improvements in Hair-Drying Combs; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 My invention relates to combs for drying the hair, and has for its object to provide improved features of construction whereby the wick which receives the fuel for heating may be readily placed in the chamber provided therefor and replaced by another when desired and will be entirely inclosed, and in which the openings for the escape of the flame to heat the teeth will be shielded or protected so that the hair will not come in 20 contact with the wick or be liable to become caught or entangled by any portion of the comb, and in which also the heating flame will be directed or projected alongside the teeth so as to more quickly and efficiently 25 heat the same.

To the accomplishment of the foregoing and such other objects as may hereinafter appear the invention consists in the features 30 hereinabove particularly described and then sought to be clearly defined by the claims, reference being had to the accompanying drawing forming a part hereof and in which—

Figure 1 is a longitudinal section through 35 the comb; Fig. 2, a side elevation thereof; Fig. 3, a cross section on the line 3—3 of Fig. 2.

In the drawing the numeral 1 designates the back of the comb; 2, the teeth, and 3, 40 the handle. The back of the comb is tubular and the handle hollow and separable from the back, being screw threaded or otherwise secured to the tubular back, so that a wick 4 may be readily introduced into the tubular back so as to lie, partially, therein and in the hollow handle. The handle 45 will hold alcohol, or other suitable fuel, and is provided with a filling nozzle 5 having a screw cap 6. The tubular back is formed

with one or more openings or slits 7, preferably at opposite sides which communicate with the interior of the back. These openings are formed on the underside of the tubular back, to one side of the base of the teeth, so that the overhanging sides 8 thereof 55 will form or constitute shields which will tend to direct or deflect the flame against the teeth 2 or along the sides thereof and thus more quickly and efficiently heat the teeth than otherwise would be the case. By 60 thus locating the openings the liability of the hair coming in contact with the wick as the comb is drawn through the hair is obviated, and also the clogging of the openings and the liability of the hair to become caught 65 and entangled or wedged in the openings is prevented. It will be observed that the wick is practically entirely inclosed or incased within the tubular back so that wastage of the fuel by evaporation is reduced to 70 the minimum.

In operation, heat, by means of a match or other means, is applied to the back of the comb so as to vaporize the fuel with which the wick is impregnated or saturated, and 80 the vapor issuing through the opening is then ignited so that the flame will be directed alongside the teeth, in the direction of their length. When the comb has become sufficiently heated, the flame is extinguished 85 and the comb drawn through the hair of the head so as to dry the same, and thus the hair may be dried in a comparatively short time after being shampooed and without injury to the hair.

The drying comb may be made of any 90 suitable material and configuration and the details may be varied without departing from the invention as defined in the appended claims.

Having described my invention and set forth its merits, what I claim is—

1. The within described heating comb comprising a tubular back and hollow handle in communication with each other 100 and teeth projecting from one side of the tubular back, the tubular back being formed between the base of the teeth and overhanging sides of the back with openings communicating with the interior of the 105 back at one side of the teeth.

2. The within described heating comb comprising a hollow back having teeth pro-

jecting therefrom and provided with openings along opposite sides of the base of the teeth between said base and overhanging sides of the back, and a hollow handle in communication with the tubular back and having a filling opening and separably connected to the tubular back.

In testimony whereof I affix my signature in presence of two witnesses.

CURT KRIEGER.
